153,295

DESIGN FOR INFANT'S SHOE

William Kaut, Jr., Louis F. Lauman, and
Frank J. Winter, Jr., Dixon, Mo.

Application August 18, 1948, Serial No. 148,158

Term of patent 14 years

(Cl. D7—7)

To all whom it may concern:

Be it known that we, William Kaut, Jr., Louis F. Lauman, and Frank J. Winter, Jr., citizens of the United States, residing at Dixon, in the county of Pulaski, State of Missouri, have invented a new, original, and ornamental Design for an Infant's Shoe, of which the following is a specification, reference being had to the accompanying drawing, forming part thereof.

Figure 1 is a plan view of a shoe embodying our new design;

Figure 2 is a side elevation of the shoe;

Figure 3 is a toe-end view;

Figure 4 is a heel-end view; and

Figure 5 is a perspective view taken from the rear inside of a shoe embodying the present design.

We claim:

The ornamental design for an infant's shoe, substantially as shown.

WILLIAM KAUT, JR.

LOUIS F. LAUMAN.

FRANK J. WINTER, JR.
